UNITED STATES PATENT OFFICE.

ERNST W. VOGT, OF SILVERTON, OHIO.

DOWNSPOUT CUT-OFF.

1,328,348.

Specification of Letters Patent. Patented Jan. 20, 1920.

Application filed June 16, 1916. Serial No. 104,001.

To all whom it may concern:

Be it known that I, ERNST W. VOGT, a citizen of the United States, and a resident of Silverton, in the county of Hamilton and 5 State of Ohio, have invented certain new and useful Improvements in Downspout Cut-Offs, of which the following is a full, clear, and exact description, reference being had to the accompanying drawing, forming part 10 of this specification.

My invention relates to downspouts for conducting rain water in particular, and more specifically to valves for directing the flow of such water after it leaves the spout. 15 In many cases rain water is used for cisterns, and is the sole supply from which cisterns are filled. The first water from a roof is dirty, as it carries with it the accumulated dirt and dust since the previous rain, 20 and this water is not desirable for use in a cistern. Accordingly valves are often interposed between the end of a downspout and the pipe leading to the cistern, permitting the water to be turned aside from running 25 into the cistern pipe until the roof is clean.

The operation of these valves is an annoyance, and they are usually turned to let water into the cistern and allowed to remain in this way, unless some one at the 30 time that a rain begins goes out and makes the proper adjustments, and at the least they require attention at just the times when it is not desirable to be out of doors.

It is the object of my invention to provide 35 a downspout valve which operates automatically to turn the first quantity of water running down the spout into the drain pipes, and then to automatically shift to turn the balance of the rain into the cistern pipe.

40 This object and other advantages to be noted I accomplish by that certain construction and arrangement of parts to be herein-after more specifically pointed out and claimed.

45 In the drawing,

Figure 1 is a front elevation of the device, partly broken away.

Fig. 2 is a side elevation of the same, also partly broken away.

50 Fig. 3 is a top plan view thereof.

1 is the down-spout pipe running from a roof or the like and carrying rain water. 2 is a cylindrical casing in the upper end of which is mounted a pipe 3 that extends into

the casing and is connected to the downspout 55 at the exterior thereof.

Mounted within the casing on a pin 4 that extends across between the two sides thereof, or in any other desired manner is a revolvable drum 5 of less size than the casing, and 60 having an opening 6 at the upper side thereof into which protrudes the pipe 3. This drum has an opening 7 in the lower portion thereof for the escape of water flowing in through the pipe 3, and a partition 8 65 is mounted in the base of the cylindrical casing. On either side of the partition are openings for pipes 9 and 10, leading to the cistern and to the drain respectively. Accordingly when the drum is revolved around 70 so that the opening 7 is over the pipe 9 then water will flow into the cistern, as the partition will prevent it flowing into the drain pipe, and vice versa when the drum is revolved back so that the opening lies at the 75 other side of the partition.

For maintaining the drum with the opening normally over the drain pipe 10, a weight 11 is mounted on the left side thereof. To swing it to the left for allowing the cistern to get the water, a chamber 12 is formed at the right side of the drum. Inside the pipe 3 is mounted a narrow flanged plate 13, having its flange extending upwardly to form a ledge on which water will collect 85 when flowing down the pipe 3. The plate is set in a slanting position, and opening at the lowest point thereof is a small pipe 14 which enters the pipe 3 just above the plate and into the small annular channel formed 90 by its flange. The pipe 14 leads into the chamber 12 and serves to slowly fill it with water.

The channel and chamber are so proportioned that when enough water has escaped 95 into the drain to clean off the roof from whence it comes, then the weight of the water in the chamber will counterbalance the weight and cause the drum to revolve to its cistern connecting position.

100 A small bleed hole 15 is formed in the bottom of the chamber, and over this bleed hole is placed a cover plate 16 having an outlet that is controlled by a small ball valve 17. Thus while the bleed will be so slow 105 that allowance can be easily made for it in filling the chamber, it will allow the chamber to drain when a rain has stopped for any

length of time by the seepage of water under the ball. Of course as soon as sufficient water has seeped out of the chamber, the weight will revolve the drum to its normal 5 position.

For locking the drum in a desired position, an arm 18 is mounted on the top thereof, which arm extends out through a slot in the casing 2. A ring 19 hinged on 10 the outside of the casing is so positioned that it can be swung over the top of the arm, thereby holding the drum in position to turn water into the drain pipe 10. The arm may be provided with a hole 20, and a pin 21 may 15 be slidably mounted on the casing in a position to engage the hole, thereby holding the casing up against the weight in cistern filling position.

Various modifications could be made in 20 my device without departing from the spirit thereof, and I do not wish to be limited in my claims that follow because of a failure to mention such modifications.

Having thus described my invention, what 25 I claim as new and desire to secure by Letters Patent, is:

1. A downspout cutoff comprising a casing having an inlet and outlets for waste and cistern, a drum rotatably mounted in 30 the casing and adapted to direct the inlet

water to either outlet, a counterbalance to maintain the drum in normal position to deflect the water to the waste outlet, and a water container in said drum comprising a chamber arranged peripherally of the drum, 35 and having a bleed hole and a ball for said bleed hole, a narrow ledge-forming member in the inlet, and a pipe leading from said ledge into said chamber, said pipe being bent in an arc to conform to said peripheral 40 chamber, said water container adapted when filled to revolve the drum to direct the inlet water to the cistern outlet.

2. A means for controlling the flow of water in a downspout cutoff comprising a 45 rotary drum having a chamber disposed along its periphery, said chamber being open at the top and closed at the bottom by two interspaced members having central bleed holes therein, and a ball intermediate said 50 members, a ledge-forming member to trap a small quantity of water comprising a ring-shaped member to fit an inlet pipe, having a beveled edge adapted to form a channel in coöperation with such pipe, and a pipe leading from such channel to the chamber, said pipe being disposed in an arc to conform to the shape of the drum.

ERNST W. VOGT.
